UNITED STATES PATENT OFFICE.

GEORGE W. LYNN, OF DETROIT, MICHIGAN.

CAPPING APPARATUS.

No. 867,890.

Specification of Letters Patent.

Patented Oct. 8, 1907.

Application filed May 7, 1906. Serial No. 325,104.

To all whom it may concern:

Be it known that I, GEORGE W. LYNN, a citizen of the United States of America, residing at Detroit, in the county of Wayne and State of Michigan, have invented new and useful Improvements in Capping Apparatus, of which the following is a specification.

This invention relates to a machine for applying screw caps to cans, jars, bottles and other containers using closures of this character, the object of the invention being to provide an apparatus of simple construction, whereby the operation of applying the caps may be conveniently, efficiently, expeditiously and inexpensively performed.

One form of apparatus embodying my invention is shown in the accompanying drawings, in which—

Figure 1 is a front elevation of the apparatus. Fig. 2 is an end elevation thereof. Fig. 3 is an enlarged vertical front to rear section on line 3—3 of Fig. 1, showing one of the sets of devices for feeding the caps to the cap-holders and opening said holders to receive and release the caps. Fig. 4 is a vertical longitudinal section through the cap feeding, holding and releasing devices. Fig. 5 is a sectional plan view thereof. Fig. 6 is a detail section showing one of the rotary can holders 25 and one of the cams for raising and lowering the table. Fig. 7 is a top plan view of one of the rotary can holders. Fig. 8 is a vertical section showing the construction of a can holder and the means for automatically opening and closing the clamping jaws thereof. Fig. 9 is a detail vertical section through the table and drive gear of the train of gears for rotating the jar-holders, showing the means for connecting said gear for movement with the table. Fig. 10 is a sectional plan view on line 10—10 of Fig. 9.

The frame of the machine may be of any suitable construction, but as shown in the present instance, comprises a pair of supporting standards 1 and 2, constructed and tied in any preferred manner to secure strength and stability. Supported from these standards at the front of the frame is a shelf 3 on which the containers to which caps are to be applied are supported prior to their application to their rotary holders for the attachment of the caps thereto.

Journalized in the lower portion of the frame is a transverse drive shaft 4 equipped with fast and loose pulleys 5 and 6 for connection with a driving belt. On this shaft are gears 7 and 8 meshing respectively with a pinion 9 on a vertical shaft 10 and a gear 11 on a vertical shaft 12, said vertical shafts being arranged at the opposite sides of the frame. The gear 7 is a mutilated gear, having but a portion of its periphery provided with teeth to mesh with the pinion 9, to intermittently rotate the shaft 10 a prescribed number of times upon each complete rotation thereof.

The shafts 10 and 12 extend upward through a vertically movable carriage or table 13 which slides thereon

and carries a series of rotary holders or supports 14 for the cans or containers to which the caps are to be applied, each of said holders or supports comprising a gear wheel having a depending hub 15 resting on the table and journaled on a pivot bolt 16 carried by the table, the holders being rotated in unison from the shaft 10 by a gear 16' on the upper end of said shaft, coaxing intermeshing gears 17 and 18 which mesh with the teeth of the adjacent holder and toothed idlers 19 which communicate motion from one holder to the other throughout the series, the gear 16' being connected with the table and slidably mounted on the upper angular end 10' of shaft 10 to maintain continuous engagement with the gear 17 as the table 13 rises and falls. The connection between the table and gear 16' comprises, as shown in Figs. 9 and 10, guide fingers 13* on the table projecting into the groove of an annularly-grooved collar or sleeve 13^b depending from the gear, whereby the gear is permitted to rotate with the shaft while shifted up and down on the part 10' as the table rises and falls. A head or disk 20 is suitably secured to and spaced from the upper surface of the rotary holder 14 and is designed to fit within the bottom recesses of cans and containers to center the same in position upon the holder.

On the holder is a clamp comprising a pair of jaws 21 and 22 adapted to grip the container to hold it in position thereon during the operation of applying the cap, said jaws being provided with arms 23 projecting in opposite directions and sliding in a guide space formed between the holder and disk 20. The free ends of the arms are formed with depending trip portions 24 which extend downward through and are movable in slots 25 in the holder to adapt the jaws to be radially adjusted to clamp and release the can. Interposed between these trip portions and the hub 15 are expansion springs 26 which serve to adjust the jaws toward each other to grip the can. The jaws are retracted to release the can at the limit of the downward movement of the table by retracting blocks or members 27 having beveled surfaces to engage the trip portions 24 to gradually force the same inwardly and thereby spread the jaws apart. A horizontal shaft 28 is arranged below a stationary bar 29 on which the retracting members 27 are arranged and carries cams 30 which raise and lower the table 13 with the can holders thereon. The shaft 28 is driven from the shaft 12 by intermeshing gears 31 and 32.

Arranged above the table is a stationary bar or support 33 on which the cap-feeding and holding devices are supported, said devices being disposed immediately above and equal in number to the can holders. Each of these devices comprises a feed chute 34 in which a column of caps is stacked, which feeds downward by gravity therein. The chutes 34 are each provided with slots 35 through which the number of caps contained in the holder may be readily determined at any time; and

are supported by upper and lower transverse bars 36 and 37 and brackets 38 fixed to the bar 33. The bar 37 supports the columns of caps and forms a guide shelf for the feed of the caps therefrom to the cap holders, the feeding operation being accomplished by the mechanism hereinafter described. Each cap holder comprises a pair of segmental gripping jaws 39 carried by arms 40 pivotally mounted upon a head 41, and having their upper ends flared or outturned and normally forced apart by springs 42 carried by the head to maintain the jaws 39 in gripping position. The head 41 is arranged upon the lower end of a stem 43 slidable vertically through an opening in the bar 33 and through a guide bracket 44 carried by said bar. A coiled spring 45 surrounds the upper portion of the stem between a nut 46 theron and the head of the bracket and normally maintains the cap holder in a determined position. If during the upward movement of the table 13 to bring the cans in receiving position, excess pressure is exerted by the threaded necks of the cans on the caps held by the cap holders, the latter will recede upwardly against the resistance of the springs, thus allowing an automatic adjusting and cushioning action to compensate for slight variations in the heights and sizes of the cans and caps. Retracting blocks 47 are arranged in pairs between the cap holders and are slidably mounted in a dovetailed groove 47^a on the bar 33 through the medium of guide bolts or screws 48 projecting through slots in said blocks and serving to retain the same in position. The blocks are arranged to bear upon the outwardly curved upper ends of the arms 40 and are adapted to be moved inwardly and outwardly toward the respective arms of the holders to swing the jaws 39 open and permit them to be closed by the springs 42. The meeting faces of the pairs of jaws are adapted to be engaged by wedge-shaped spreaders 49 movable in unison and carried by a supporting bar or plate 50, between which and the bar 33 are one or more springs 51 which serve to move the plate 50 outwardly from said bar 33 and thereby retract the spreaders 49 to permit the cap-holding jaws to be closed by their closing springs.

Secured to and rising from the bar 33 are curved brackets 52 and 53 on which are pivotally hung links 54 and 55. The link 54 is connected to a series of rods 45 56 which transfer motion therefrom to plungers 57 slidably mounted on the shelf 37 and adapted on their forward movement to force the bottom caps 58 of the columns of caps in the chutes 34 between the jaws of the respective cap holders. To the link 54 is connected 50 one end of a rod 59 which slides between guide rollers 60 supported by a bracket secured to the bar 36, which rod 59 is provided at its opposite end with a strap or shoe 61 adapted to be engaged by a cam 62 on a shaft 63 driven from the shaft 12 by intermeshing gears 64 and 65. This shaft rotates rearwardly and the point of the cam is adapted to come in contact with the shoe 61 and slide the rod 59 forward, whereby motion will be transmitted to the link 54 to project all of the plungers 57. When the heel of the cam engages the shoe the 60 rod 59 is drawn rearwardly by a retracting spring 64 connecting the same with the bracket arm 62, whereby the plungers will be simultaneously retracted and reset for further operation. The link 55 is pivotally connected with a rod 66 having a yoke 68 in which is slidably mounted a shoe 67 adapted to be engaged by a

cam 68 on the shaft 63, said shoe being adjustable through the medium of set screws 69 adapted to be secured in adjusted position by lock nuts 70. The cams 62 and 68 are so arranged upon the shaft 63 as to properly operate at timed intervals during the rotation of the shaft 63, which is driven continuously by the drive gearing, to successively operate the plungers to feed the caps into the jaws 39, retract the blocks 47 to allow said jaws to grip the caps, and finally after the caps are applied to the cans open the jaws 39 to release the caps 75 and maintain said jaws open for the next succeeding operation. Two sets of these cam operating devices are preferably employed and arranged a suitable distance apart to insure a proper uniform motion of the plungers and spreaders. The inner faces of the jaws 80 39 are preferably serrated in practice in order to adapt them to grip the cap tightly enough to hold them during the action of screwing the same upon the cans, while permitting the caps to slip when they are screwed on to the fullest extent. This feature in connection with the feature of yieldingly mounting the cap holders insures a nicety of operation and effectually prevents jamming of the threads and liability of breakage of the cap or can when said parts are brought together.

In operation, the cans are applied to their rotating holders 14 while the table 13 is at the limit of its downward movement and when the teeth on the drive gear 7 engage the pinion 9 the holders and cans will be rotated a sufficient number of times and no more to 95 thread the necks of the cans into the caps, it being understood that prior to this operation the plungers operate to feed the caps in position for application, while the table 13 is raised by the cams 30 to elevate the cans to bring their necks into position to receive the caps. 100 As soon as the table begins to move upwardly the clamping jaws 21 and 22 on the can holder are released by the retracting devices 27 and thrown by the springs 26 into engagement with the can to fix the same to the holder 14 to rotate therewith when the gear 7 comes into action. As soon as the caps are applied to the set of cans fed-up in the manner described the motion of the holders 14 is arrested by the movement of the teeth of the gear 7 out of engagement with the pinion 9, and immediately thereafter the table 13 110 will descend under the action of the cams. Just prior to the beginning of the descending movement of the table the spreaders 49 come into action and open the cap holders to release the jaws thereof from the applied caps, after which the plungers operate to feed a new 115 set of caps into the holders for the succeeding operation. The table 13 remains at rest in its lowered position a sufficient time to allow the operator to remove the capped cans and substitute an equivalent number of cans to be capped, the capped cans being released 120 and the succeeding set of cans clamped on the ensuing upward movement of the table in the manner previously described. The gear 7 then comes into action and the above described operation is repeated.

It is thought that the construction and mode of operation of the apparatus will be fully understood from the foregoing description, taken in connection with the accompanying drawings, and that it is apparent that the invention provides a machine by which the operation of applying screw caps to cans, jars, bottles, and other 125 130

containers using this form of closure may be quickly and conveniently effected.

Having thus described the invention, what is claimed as new, is:

- 5 1. In a machine of the character described, the combination of a relatively stationary yieldingly mounted cap holder, a container holder movable from and toward the cap holder, means for automatically opening and closing the cap holder, means for feeding caps thereto, and means for rotating the container holder to effect the application of the cap. 55
- 10 2. In a machine of the character described, the combination of a rotary container holder, a cap holder, means for automatically opening and closing the same, means for feeding caps to the cap holder, means for moving the container holder toward and from the cap holder, means for rotating the container holder, and means for automatically clamping the container to and releasing it from its holder. 60
- 15 3. In a machine of the character described, the combination of a supporting frame, a series of cap holders mounted upon the frame, a table movable toward and from said cap holders, jar holders carried by the table, means for automatically feeding caps to said cap holders, means for closing said holders, means for moving the table toward the cap holders and closing the jar holders thereon, means for rotating the latter to secure the caps upon the jars, means for releasing the caps from the cap holders, means for releasing the capped jars from their holders, means for operating the table, and primary actuating mechanism for operating the several parts in timed relation. 65
- 20 4. In a machine of the character described, the combination of a supporting frame, cap holders carried by the frame, means for feeding caps to the cap holders, means for opening and closing said cap holders, a table movable toward and from the cap holders, jar holders upon the table, means for automatically opening and closing said holders, means for rotating the jar holders when the jars are moved to cap-applying position, and means for operating the several parts in timed succession. 70
- 25 5. In a machine of the character described, the combination of a supporting frame, a cap holder carried by the frame, means for feeding the caps thereto, a table movable toward and from the cap holder, a jar holder carried by the table, means for operating the table, means for rotating the jar holder when the jar comes into cap-applying position, and means for releasing the applied cap from the cap holder and the jar from the jar holder. 75
- 30 6. In a machine of the character described, the combination of a supporting frame, a series of cap holders carried thereby, means for opening and closing said holders and feeding caps thereto, a table movable toward and from 80
- 35 said cap holders, rotary jar holders carried by the table, means for opening and closing said holders, and gearing for the operating parts including a mulfated drive gear arranged to impart a prescribed number of rotations to the jar holders. 85
- 40 7. In a machine of the character described, the combination of a supporting frame, cap holders yieldingly mounted thereon, each holder comprising movable gripping jaws, means for opening and closing said jaws, means for feeding caps thereto, a table movable toward and from the cap holders, rotary jar holders carried by the table, means for opening and closing said holders, and means for operating the several parts at timed intervals to feed the caps, close the cap holders, move the table toward the cap holders, 90
- 45 rotate the jar holders, release the applied caps, retract the table and open the jar holders. 95
8. In a machine of the character described, the combination of a supporting frame, cap holders carried thereby, a table movable toward and from the cap holders, jar holders carried by the table, means for automatically feeding caps to the cap holders, means for operating the table and opening and closing the holders, and means for rotating the jar holders to effect the application of the caps thereto.
9. In a machine of the character described, the combination of a supporting frame, a series of cap holders carried thereby, each comprising pivoted spring closed clamping members, means for periodically opening and closing said members, means for feeding the caps to the cap holders when the members thereof are open, a table movable toward and from the cap holders, rotary jar holders carried thereby, each embodying spring closed clamping arms, means for operating the table and rotating the jar holders when the jars are brought into cap-applying position, means for releasing the jars from the holders, and drive gearing for the operating parts. 80
10. In a machine of the character described, the combination of a supporting frame, cap-feeding means, cap-holders cooperating therewith, jar holders movable vertically toward and from the cap holders, means for projecting, retracting and rotating the jar holders, and drive gearing for operating the parts at timed intervals to feed caps to the cap holders, move the jar holders to cap applying position, rotate said holders to screw the caps thereon, release the applied caps and retract the jar holders and release the jars therefrom. 85

In testimony whereof, I affix my signature in presence of two witnesses.

GEORGE W. LYNN.
